UNITED STATES PATENT OFFICE.

ADA ETHEL FAIN, OF BRONDESURY, LONDON, ENGLAND.

DESIGN FOR A DINNER WAGON.

Application filed August 5, 1925. Serial No. 14,318. Term of patent 14 years.

To all whom it may concern:

Be it known that I, (Mrs.) ADA ETHEL FAIN, a British subject, residing at 29 Mowbray Road, Brondesbury, London, N. W. 6, England, have invented and produced a new, original, and ornamental Design for a Dinner Wagon, of which the following is a specification, reference being had therein to the accompanying drawing, forming part thereof.

The figure is a perspective view of a dinner wagon, showing my new design.

Having described my invention, what I claim as new, and desire to secure by design Letters Patent is:—

The ornamental design for a dinner wagon as shown.

Dated this 22nd day of July, 1925.

In testimony whereof I have affixed my signature.

ADA ETHEL FAIN.
